CLAIM

The ornamental design for a cookware, as shown and described.

DESCRIPTION

FIG. 1 is a front right perspective view of the cookware showing the new design;

FIG. 2 is a front elevation view thereof;

FIG. 3 is a back side elevation view thereof;

FIG. 4 is a right side elevation thereof;

FIG. 5 is a left side elevation thereof; and,

FIG. 6 is a top plan view thereof.

The broken lines in the drawings are for illustrative purposes only and form no part of the claimed design.
